WILFRED M. BYWATER, OF WEEHAWKEN, NEW JERSEY, ASSIGNOR TO THE BARRETT COMPANY, OF NEW YORK, N. Y., A CORPORATION OF NEW JERSEY

DISTILLATION OF TAR AND RECTIFICATION OF THE DISTILLATE THEREFROM

Application filed August 31, 1928. Serial No. 389,673.

This invention relates to the distillation of tar by direct contact with hot gases, and rectification of the distillate therefrom. It includes both the new method and apparatus.

5 According to this invention, tar is distilled by direct contact with hot gases, the gases and vapors resulting from the distillation of the tar are passed thru a rectifying column and then thru an indirect condenser 10 where they are partially cooled to separate oils from the gases and these oils are returned to the rectifying column and cause the separation of higher boiling constituents from the gases in the rectifying column. The gases 15 and vapors leaving the indirect condenser are cooled to recover one or more oils of lower boiling range which are free or substantially free from higher boiling constituents of the range which are separated from the gases in 20 the rectifying column.

The temperature of the gases and vapors passing thru the indirect condenser is controlled to cause condensation and separation of higher boiling oils, only. These oils in 25 passing down the rectifying column in contact with the upflowing distillation gases cause condensation of the highest boiling constituents carried by the gas. The lower boiling components of the oils flowing down the 30 rectifying column are volatilized and again pass with the gases into the indirect condenser. The separation of the distillate into a higher boiling fraction and one or more lower boiling fractions is such that the constituents in 35 the higher boiling fraction are free, or substantially so, from oils of the lower boiling range, and the oils of lower boiling range are free, or substantially so, from constituents of the higher boiling range.

40 The distillation of tar by hot gases contemplated by this invention is such as to yield a gas enriched with a sufficient per cent of oil vapors to lend itself to rectification and the fractional recovery of condensable constituents. The gases entering the rectifying column of this invention contain at least seven percent by volume of condensable constituents, and preferably ten or fifteen percent by volume or more, and are in substantial equilibrium with the enriching medium.

The hot gases employed for the distillation of the tar are preferably hot coal distillation gases or other hot coal gasification gases. When hot coke oven gases or other foul gases are employed for the tar distillation, the tar which is distilled to pitch is sprayed into the hot gases in the form of a fine intense spray which not only exposes a large surface of the tar to the action of the hot gases whereby the tar is distilled, but the 55 fine intense spray of the tar and pitch simultaneously scrubs and detars the gases, removing entrained tarry and pitchy particles so that on subsequent cooling of the gases the oils which separate will be clean oils substantially free from tarry or pitchy constituents.

When coke oven gases are employed for the distillation of the tar, they are advantageously employed at substantially the temperature at which they leave the ovens and 70 while they contain substantially their original vapor content. When pitch of high melting point, e. g. 300° F. or 400° E, is to be produced, the temperature of the gases employed for the distillation is such that the gases, 75 even after partial cooling as a result of the distillation are of such a temperature that they will carry from the still in the vapor state constituents of higher boiling range including compounds which are solid or semi-solid in an isolated state at ordinary temperatures. Such higher boiling compounds include not only the constituents distilled from the tar but also compounds of this boiling range present in the gases as they 80 leave the ovens. The process of this invention may be employed to advantage to separately recover such higher boiling constituents from lower boiling oils in order to obtain a high yield of oils which are free, or 85 substantially so, from such higher boiling constituents. The higher boiling compounds thus separated from the gases may be collected as a separate product, or they may be blended with the pitch produced, or they may be employed in any other way, as desired.

Where a high melting point pitch is to be produced, it is desirable to pass the hot gases and the tar to be distilled through the still in a concurrent direction while spraying the 100

tar into the gases so that the hot gases entering the still are sprayed with incoming tar which may be partially distilled before it enters the still, and the pitch which is produced after continued spraying of the tar into the hot gases will be sprayed into gases which have been cooled and enriched to some extent by the distillation and production of pitch in them. These conditions tend to prevent overdistillation of the tar or pitch and the formation of coke in the still. In producing pitch of high melting point, the tar may advantageously be distilled in two stages. In the second stage, semi-pitch from the first stage is brought into direct contact with the hottest gases and distilled to pitch of high melting point. In the first stage tar is distilled to semi-pitch by direct contact with the hot gases and vapors from the second stage. The gases which have been employed for distillation of higher boiling constituents in the second stage of the distillation are then employed for distillation of lower boiling ingredients from the incoming tar, and thus their vapor content is increased. The method of distillation and the type of still which may be employed, according to this invention, are not thus limited, however, since various types of stills and various methods of distillation may be employed.

The cooling medium employed in the indirect partial condenser following the rectifying column according to this invention may be water or tar or any other desired fluid. Tar may advantageously be employed as the cooling medium and the tar thus heated may be fed to the still or it may be sprayed into the gas saturator where one is employed. Heat economy is thus effected and the capacity of the apparatus for distillation is increased.

The invention will be further described in connection with the accompanying drawings, in which it is applied to the distillation of tar in hot coal distillation gases, and the rectifying of the resulting vapors. It is intended and is to be understood, however, that the invention is not limited thereto.

In the drawings,

Fig. 1 is a plan view of one application of the invention;

Fig. 2 is an elevation of the apparatus shown in Fig. 1;

Fig. 3 is a cross-section thru the still of Fig. 2; and

Fig. 4 is an elevation of a modified form of apparatus.

In the drawings, 5 is a coke oven battery. The individual ovens of the battery are connected thru the uptake pipes and goose necks 6 with a collector main 7. From the collector main the gases pass thru the cross-over main 8 to condensers and means for the recovery of ammonia, etc. (not shown). This

apparatus may be of the usual type and is shown more or less diagrammatically in the drawings.

At the opposite side of the coke oven battery is a still 10. Selected ovens of the battery are connected thru the uptake pipes and goose necks 11 and the hot gas header 12 with this still 10. By the proper manipulation of valves in the uptake pipes and goose necks 6 and uptake pipes and goose necks 11, the gases from these selected ovens may be passed either thru collector main 7 to the usual by-product recovery system or thru the uptake pipes 11 and the hot gas header 12 into the still 10. The gases enter the still at approximately the temperature at which they left the ovens and with substantially their original vapor content. In the still is a roll 13 which is adapted to be driven at high speed by the motor 14. This roll when rotated a speed of 900-1200 R. P. M. for example, sprays the tar or pitch up into the hot gases passing thru the still and exposes a large surface of the tar to the distilling action of the gases and simultaneously scrubs and detars the gases, removing any entrained tarry and pitchy constituents present in the gases. The pitch produced is withdrawn from the still thru the tray 15 and the leveling arm 16. Means suited to the recovery of pitch of the melting point produced, is provided. The drawings show a trough 15' with a cold water spray 16' for granulating pitch of high melting point. By varying the position of the levelling arm 16, the depth of tar or pitch maintained within the still can be controlled, and this in turn controls the nature of the tar spray produced in the still. The tar is fed to the still thru the line 17 and passes thru the still in a direction concurrent with the flow of the gases thru the still. The roll is advantageously set at one side of the still, as shown more clearly in Fig. 3.

The hot gases and vapors leaving the still pass up thru the tower 20. This tower comprises several compartments. The bottom compartment 21, is a hot gas saturator or saturating chamber in which the gases and vapors coming from the still are sprayed with tar from the line 22 thru the nozzle 23. The tar is partially distilled and the vapor content of the gases is increased especially in oils of lower boiling range. Baffles 24 are employed with advantage to expose a large surface of the tar sprayed into the gases to the distilling action of the hot gases. The low melting point pitch produced is drawn off from the bottom of the tower thru the line 25. The hood 26 prevents the spray from passing down thru the gas passage 27 back into the still. Any particles of tar spray thrown from the roll and carried by the gases into the tower will be washed out of the gases by the tar spray in this bottom section 21 of the tower.

The gases leaving the compartment 21 pass up thru the rectifying tower 30. This tower is advantageously filled with baffling means 31, such as Raschig rings or other suitable means for exposing a large surface of oil to the action of the hot gases and vapors which pass up thru the rectifying tower.

The gases and vapors leaving the rectifying column pass to the indirect condenser 35, where partial cooling is effected, and higher boiling oils are separated from the gases and these oils are returned and refluxed thru the rectifying column. Through partial cooling by indirect contact in the condensers 35 and refluxing in the rectifying column 21 of the oils which separate in this condenser, substantially complete separation of the higher boiling constituents from the lower boiling constituents is obtained.

20 A cooling medium such as water or tar is passed thru the partial condenser 35. This cooling medium enters at 36 and is drawn off at 37. The amount of cooling medium passed thru this partial condenser is so controlled by the valve 38 as to maintain the gases and vapors passing to the condensers at a constant desired temperature, and thus to condense and separate from the gases higher boiling oils which it is desired to reflux thru the rectifying tower in order to produce the desired fractionation. The high boiling fraction which collects in the bottom of the rectifying tower is drawn off thru the line 39 and may be separately collected in the tank 40 or may be used as desired. For example, all or part of this fraction may be returned to the system for redistillation, e. g., to the saturator 21, or the still 10.

40 The hot gases and the vapors which pass thru the indirect condenser 35 are conducted thru the main 45 to the condenser 46. This condenser may be of any suitable type. A direct condenser in which the gases are sprayed with water from the line 47 is here shown. One total oil or several oil fractions may be collected in this condensing system. The oils and any non-volatilized cooling medium which collect in the bottom of the condenser are drawn off into one or more decanters 48 and the oils are separately collected in the storage tank or tanks 49. Tanks 50 are provided for collecting ammonia liquor from the decanters. An exhauster 51 is provided for drawing the gases and vapors thru the system. Means for the recovery of ammonia and light oils, etc. are located beyond this exhauster.

50 The saturating chamber 21, the rectifying column 30 and the partial condenser 35 are here shown as being located one on top of another in a column. This arrangement is not essential to the invention. The saturator may be omitted, the gases and vapors may leave the still, or the saturator where one is employed, thru a main and pass thence

to the rectifying tower which may be situated where desired. Although the partial condenser 35 need not be located directly over the rectifying tower and oils condensed and separated from the gases by contact with the cooling coils in the partial condenser may be pumped and sprayed into the rectifying tower 30, the partial condenser is advantageously situated directly over the rectifying tower so that oils which separate from the gases in the condenser pass by gravity into the rectifying tower.

55 The uptake pipes 11, the hot gas header 12, the still 10, the spray chamber 21 and the rectifying tower 30, are advantageously heavily insulated, as indicated at 52, to prevent loss of heat by radiation.

10 The boiling range of the fraction drawn off thru the line 39 into the tank 40 is controlled by the amount and temperature of the gases passing thru the still and the saturator, the amount of tar sprayed into the gases thru the nozzle 23, the nature of the tar distilled and the melting point of the pitch produced, etc., as well as by the amount of cooling medium passed thru the partial condenser 35.

15 Fig. 4 shows a coke oven battery 5a, the selected ovens of which are connected thru the uptake pipes and goose necks 11a thru the hot gas header 12a with the still 10a. This still 10a may advantageously be situated at the opposite side of the coke oven battery from the ordinary collector main. By the regulation of valves in the uptake pipes and 20 goose necks 11a and valves in the uptake pipes and goose necks connecting these same ovens with the regular collector main, the gases from the desired number of ovens may be passed thru the hot gas header 12a into the still 10a. The still 10a is equipped with 25 a spray roll 13a and a pitch draw-off 16a similar to those described in connection with the preceding figures. The operation of the still may be as described in connection with those figures. From the still the hot gases and vapors pass up thru the tower 60. This tower comprises three compartments, the saturator 61, the rectifying column 62 and the partial condenser and tar preheater 63. From the partial condenser the hot gases and vapors pass thru the main 64 to any suitable type of condenser.

30 Tar is fed thru the line 65 to the partial condenser 63 which is an indirect condenser or heat interchanger in which the gases and vapors are cooled and in which tar entering at 65 is simultaneously preheated. This preheated tar drawn off the condenser thru the line 66 is sprayed into the gases in the saturator 61 thru the nozzle 67. Additional tar may be added to the line 66 thru the line 68. Baffles 69 are provided to insure exposing a large surface of the preheated tar to the action of the hot gases. The tar is partially dis-

tilled in the saturating chamber and the distillation residue, which may be a low melting point pitch, is drawn off from the bottom of the tower thru the line 70. A part of this distillation residue may if desired be separately collected in the tank 71 as a low melting point pitch product. The remainder or all of the partially distilled tar is fed into the still 10a thru the line 72. The tar entering at 72 has been partially distilled in the saturator 61 by direct contact with the hot gases and vapors leaving the still and at least a part of the tar has been preheated in the indirect condenser 63.

15 The gases and vapors leaving the saturator 61 pass up thru the rectifying column 62 and are partially cooled in the heat interchanger 63. Oils which are condensed and separate from the gases pass down thru the rectifying column over the baffling means 74. The large surface of contact between the oil and hot gases and vapors in the rectifying tower provides rectification and sharp fractionation of the oils so that the heavy oil condensate, which 20 collects in the bottom of the rectifying column 62 and is drawn off thru the line 75 into the storage tank 76, is an oil of relatively high boiling range, and represents the highest boiling oil fraction collected from the system. 25 Its character will depend upon the character of the tar distilled, the degree of fractionation employed, the melting point of the pitch made, etc.

25 The amount of gases passing thru the still, the nature of the tar distilled in the still, the melting point of the pitch produced, etc. control the temperature of the gases and vapors entering the saturator thru the passage 78. The amount to which these gases and vapors 30 are cooled in the saturator is controlled by the temperature and amount of tar sprayed thru the nozzle 67 and the efficiency of the baffling means. By controlling the fraction of low melting point pitch which is separately 35 collected in the storage tank 71, the saturator and still may be operated as different units to produce pitches of different desired melting points. Similarly, by controlling the amount of tar passed thru the partial condenser 63 and where possible, controlling the 40 temperature of the tar passed thru this condenser, the cooling effected in the condenser and consequently the amount of oils condensed and refluxed thru the rectifier is controlled; this step may be made independent of the distillation which is effected in the saturator 61 and in the tar still 10a by passing any desired proportion of the tar thru the 45 heat interchanger 63 and adding the balance to the system thru the line 68. The tar supplied thru 68 may be tar of the same kind and temperature as that supplied thru the line 65, or tar of a different kind or different temperature may be employed. The control of

the tar thru these two lines is regulated by the valves 79 and 80.

Although the invention is more particularly described herein as applied to the distillation of tar by hot coke oven gases, it is not limited thereto and may be applied to advantage to tar distillations employing the heat of other waste gases, for example, hot gas retort gases, hot water gas, hot producer gas, etc. Where hot coal gasification gases are employed, they are used at substantially the temperature at which they leave the ovens or retorts and while they contain substantially their normal vapor content, i. e. before the removal of an appreciable amount of tar or pitch therefrom. Because of the intensive tar spray to which they are subjected, and because of the thorough flushing of the walls of the still as provided in the apparatus shown, apparatus of this type may be employed for distilling tar with gases of a temperature sufficiently high to cause coking of the pitch formed if this spraying and flushing were not provided. When gases of such a high temperature are used the tar and gases are advantageously passed thru the still in a concurrent direction so that the fresh tar is sprayed into the hot gases and the partially distilled tar is sprayed into gases which have already been somewhat cooled and which are partially saturated with vapors from the previous use of the gases for distillation of the incoming air.

I claim:

1. The method of distilling tar from a coal distillation or gasification plant and rectifying the distillate therefrom, which comprises bringing the tar into direct contact with hot gases to effect distillation thereof and to produce pitch, passing the resulting gases and vapors thru a rectifying column and rectifying them therein, and then thru an indirect condenser where they are partially cooled by indirect heat exchange with a suitable cooling medium, thereby separating condensable constituents from the gases, bringing this condensate into direct contact with the gases passing thru the rectifying column, and then cooling the gases leaving the indirect condenser to separate lower boiling oils therefrom.

2. The method of distilling tar from a coal distillation or gasification plant, which comprises spraying tar into hot coal distillation gases at a temperature at which they retain substantially their original vapor content, thereby distilling the tar and producing pitch, and simultaneously scrubbing entrained impurities from the hot gases, passing the resulting gases and vapors thru a rectifying column and rectifying them therein and then thru an indirect condenser and cooling the gases therein to produce a condensate, preheating the tar by indirect heat exchange with the gases and vapors in this condenser,

spraying the condensate from this condenser into the gases and vapors in the rectifying column, and cooling the gases and vapors leaving the indirect condenser to condense 5 oils therefrom.

3. The method of distilling tar from a coal distillation or gasification plant and rectifying the distillate therefrom, which comprises spraying tar into hot coke oven gases at a 10 temperature at which they retain substantially their original vapor content to distill the tar to pitch and enrich the gases to a vapor content of at least seven per cent by volume and bring them into approximate equilibrium 15 with the distilled tar, passing these enriched gases thru a rectifying column and rectifying them therein and then thru an indirect condenser, where only partial cooling of the gases is effected and a condensate produced, 20 and then thru a further condensing system, and spraying the condensate from the indirect condenser into the rectifying column.

4. The method of distilling tar from a coal distillation or gasification plant and rectifying the distillate therefrom, which comprises spraying tar into hot coke oven gases at a 25 temperature at which they retain substantially their original vapor content to distill the tar to pitch and enrich the gases to a vapor content of at least ten per cent by volume and bring them into approximate equilibrium with the distilled tar, passing these enriched gases thru a rectifying column and rectifying them therein and then thru an indirect 30 condenser, where only partial cooling of the gases is effected and a condensate produced, and then thru a further condensing system, and spraying the condensate from the indirect condenser into the rectifying column.

40 5. The method of distilling tar from a coal distillation or gasification plant, first to semi-pitch and then to pitch of high melting point, and rectifying the distillate therefrom, which comprises passing semi-pitch and hot gases 45 thru a still in a concurrent direction, spraying and respraying the semi-pitch into the hot gases, whereby it is distilled and pitch of high melting point is produced, drawing off the pitch, bringing the gases and vapors from 50 the pitch distillation into direct heat exchange with tar, whereby the tar is partially distilled and the semi-pitch is produced, passing the resulting gases and vapors thru a rectifying column, partially cooling the gases and vapors 55 leaving the rectifying column by indirect heat exchange with a suitable cooling medium to separate condensable constituents therefrom, bringing the condensate thus obtained into direct contact with the hot gases and vapors in the rectifying column, and subjecting the gases and vapors leaving the indirect condenser to further cooling to separate lower boiling constituents therefrom.

60 6. The method of distilling tar from a coal distillation or gasification plant, first to semi-

pitch and then to pitch of high melting point, and rectifying the distillate therefrom, which comprises spraying semi-pitch into direct contact with hot coke oven gases at a temperature at which they retain substantially 70 their original vapor content, passing the hot gases and the semi-pitch thru a still in a concurrent direction while spraying and respraying the semi-pitch into the gases whereby the semi-pitch is progressively distilled to produce a pitch of high melting point and the 75 gases are scrubbed and substantially detarred, bringing preheated tar into direct contact with the gases and vapors coming from the still, whereby the preheated tar is partially 80 distilled to form the semi-pitch and the gases and vapors are further enriched in oils of low boiling range, passing the resulting gases and vapors thru a rectifying column, then partially cooling them by indirect heat exchange with the tar, whereby the tar is preheated and condensable constituents are separated from the gases, spraying this condensate into the gases and vapors in the rectifying column to effect separation of constituents 85 of higher boiling range from constituents of lower boiling range by condensing the former and allowing the latter to pass from the rectifying column to the indirect condenser, distilling the preheated tar to produce 90 the semi-pitch by bringing it into direct contact with the gases and vapors resulting from the production of the high melting point pitch, and cooling the gases and vapors leaving the indirect condenser to separate condensable constituents of lower boiling range 95 therefrom.

7. The method of distilling tar from a coal distillation or gasification plant and rectifying the distillate therefrom, which comprises 100 spraying tar into hot gases, thereby producing a pitch of high melting point, and enriching the oils in vapors comprising vapors of higher boiling constituents which are solid or semi-solid in an isolated state at ordinary 105 temperatures, passing the enriched gases thru a rectifying column and then thru an indirect condenser, separating oils of higher boiling range and constituents which are solid or semi-solid in an isolated state in the 110 indirect condenser, spraying this condensate into the gases and vapors passing up thru the rectifying column to separate therefrom constituents which are solid or semi-solid in an isolated state at ordinary 115 temperatures, and further cooling the gases and vapors leaving the indirect condenser to condense therefrom oils which are substantially free from such constituents which are solid or semi-solid in an isolated state at ordinary 120 temperatures.

8. In combination with a coal distillation plant, apparatus for the distillation of tar and the rectification of distillate therefrom, comprising a still for the distillation of tar 125

to pitch, means for passing hot coal distillation gases from the plant in to the still, a rectifying column, an indirect condenser and a further condensing system with means for 5 passing the gases and vapors from the still therethru in succession and means for returning condensate from the indirect condenser to the rectifying column.

9. In combination with a coal distillation 10 plant, apparatus for the distillation of tar and the rectification of distillate therefrom, comprising a still for the distillation of tar to pitch, means for passing hot coal distillation gases from the plant into the still, a 15 rectifying column, an indirect condenser and a further condensing system with means for passing the gases and vapors from the still therethru in succession, means for returning condensate from the indirect condenser 20 to the rectifying column, and means for passing tar thru the jacket of the indirect condenser and from there to the still.

10. In combination with a coal distillation 25 plant, apparatus for the distillation of tar and the rectification of distillate therefrom comprising a still for the distillation of tar or semi-pitch to pitch, a pitch draw-off, means for passing hot coal distillation gases from the plant to the still, means for spray- 30 ing tar into direct contact with the gases and vapors leaving the still, a rectifying column, an indirect condenser for effecting partial cooling of the vapors leaving the rectifying column, means for supplying oil 35 removed from the gases in the indirect condenser to the rectifying column, and further condensing means beyond the indirect condenser.

11. In combination with a battery of coke 40 ovens, a still, insulated means for passing hot coal distillation gases from the ovens into the still, a pitch draw-off from the still, spray means in the still to spray semi-pitch up into the hot coal distillation gases in the 45 form of an intense spray, whereby the semi-pitch will be distilled and the gases will be substantially detarred, a hot gas saturator, a gas connection between the still and the hot gas saturator, a tar spray in the saturator, and means for feeding semi-pitch produced 50 in the saturator to the still, a rectifying column thru which the gases and vapors pass from the saturator, an indirect condenser for cooling the gases and vapors leaving the rectifying column, means for bringing tar into 55 indirect contact with the gases and vapors in the indirect condenser, whereby the tar is, heated, means for supplying the heated tar to the saturator, and further condensing 60 means located beyond the indirect condenser.

In testimony whereof I affix my signature.
WILFRED M. BYWATER.

CERTIFICATE OF CORRECTION.

Patent No. 1,844,741.

Granted February 9, 1932, to

WILFRED M. BYWATER.

It is hereby certified that error appears in the printed specification of the above numbered patent requiring correction as follows: Page 1, line 73, for the letter "E" read F; page 2, line 94, for "tray" read trap, and line 115, for the misspelled word "vaports" read vapors; page 4, line 98, for "air" read tar; page 5, lines 54 and 84, claims 5 and 6, respectively, after the comma insert the words and rectifying them therein; and that the said Letters Patent should be read with these corrections therein that the same may conform to the record of the case in the Patent Office.

Signed and sealed this 22nd day of March, A. D. 1932.
